Fig. 3

The side of the mattress not shown is the same as the side shown except for the omission of the air valve.

The dominant features of my design reside in the foreshortening at the pillow end of alternate ribs so as to provide a continuous air passage transversely of the mattress adjacent the pillow, substantially as shown.

I claim:

The ornamental design for an air mattress or the like, substantially as shown and described.
